UNITED STATES PATENT OFFICE.

BENJAMIN R. COLEMAN AND LEROY B. TAYLOR, OF CHICAGO, ILLINOIS.

WINDOW CONSTRUCTION.

1,267,745.

Specification of Letters Patent.

Patented May 28, 1918.

Application filed March 24, 1915. Serial No. 16,608.

To all whom it may concern:

Be it known that we, BENJAMIN R. COLEMAN and LEROY B. TAYLOR, citizens of the United States, residing at Chicago, in the county of Cook and State of Illinois, have invented a certain new and useful Improvement in Window Constructions, of which the following is a full, clear, concise, and exact description, reference being had to the accompanying drawings, forming a part of this specification.

Our invention relates to window constructions, and especially to a window construction in which the window sash may be swung or moved outwardly instead of being slid longitudinally of the window frame.

Prominent objects of the invention are to provide a simple, practical and effective form of window construction; to arrange for the easy handling of the window sashes to open and close the same; to arrange for the easy cleaning or washing of the windows and to such end to permit the window sashes to be swung or moved in such a way that the outer surface of the window or pane of glass therein may be brought inwardly so as to permit it to be cleaned from the inside of the room or place where the window is located; to simplify the construction and reduce the cost of manufacture and installation; and to secure the foregoing and other desirable results in a simple and expeditious manner.

In the accompanying drawings Figure 1 is a longitudinal section of a window construction embodying our present invention;

Fig. 2 is a similar section showing the same in operated condition;

Fig. 3 is a front view of the window construction; and

Figs. 4 and 5 are sections taken on line 4—4 and 5—5 in Fig. 1.

The window construction shown in the drawings comprises a window frame having a vertical member 1, a lower sill 2, and a top member 3. The frame 1 is provided with longitudinally extending guideways or grooves 4 conveniently formed by strips 5 and 6, said guideways and strips being vertical in a vertical window construction such as shown. Upper and lower sashes 7 and 8 respectively are shown and these sashes have corresponding corners as for example their upper corners, referring to Fig. 1, where they are shown in closed position, provided with pins 9 and 10 respectively, arranged to fit and slide in the grooves 4. Bars or

rods 11 are connected to the pins 9 and 10 and arranged to slide in the grooves 4, whereby the ends of the sashes 7 and 8 are connected together so as to move in unison. 60 Arms or rods 12 are pivotally connected as at 13 to the window frame, preferably near the top of the upper sash when the same is in closed position. Said arms 12 are provided with laterally projecting or offset portions 65 14 which are pivotally connected near their end portions at 15 to the sides of the upper window sash 7, preferably at or near the middle portions of said sides. Other arms 16 are also connected at their upper ends to 70 the window frame, preferably at 13 where the arms 12 are supported, and these arms 16 extend downwardly to the lower sash 8 and are provided with offset or projecting end portions 17 which are connected at or 75 near their ends with the sides of the lower window sash 8, preferably at or near the middle of said sides. The vertical strips 5 are provided with cutaway portions 19 and 20 to accommodate the lateral portions or 80 projections 14 and 17 respectively on the arms 12 and 16, when said arms are in the position shown in Fig. 1.

Thus it will be seen that in this construction the two sashes 7 and 8 will move together when one or the other is actuated. When one sash is swung outwardly, as for example when the lower sash 8 is swung outwardly to the partially open position shown in Fig. 2, the lower portion of said 90 sash will swing out and the upper portion move down, and this downward movement will cause the bars 11 to lower the upper edge of the upper sash 7, and thereby swing said sash downwardly and outwardly as 95 shown in said Fig. 2. This opening or closing movement may be greater or less, as desired. By swinging one sash so as to reverse it, the other sash will also be reversed, and thus the outside of the window panes will be 100 swung inwardly and brought into a position in which they may be readily cleaned from the inside of the room. Furthermore, when in this reversed position and at all times during the movement of said sashes 105 to any adjustment, neither sash nor any part thereof will enter the room and hence screens and various other fittings may be used in or about the window frame. The reversing of the window sashes may be carried to an extent to completely close the sashes, in which case each one would occupy the position it

occupied normally or before the opening began, except that it would be upside down.

It will be understood that changes and modifications may be made without departing from the spirit of the invention.

What we claim is:

1. The combination with a window frame of a pair of sashes therein, said sashes being mounted for vertical sliding movement relatively to the window frame and also for vertical swinging movement outside of the window frame, means for connecting corresponding horizontal edges of said sashes together so that said edges may slide vertically in unison, said sash edges being pivotally connected with said connecting means, and means for supporting said sashes for swinging movement about said pivotally connected edges, whereby said sashes may be swung relatively to the window frame to more or less open or close both of said sashes simultaneously.
2. The combination with a window frame of a pair of sashes therein, sliding connections between corresponding edges of said sashes and the window frame, means for connecting said corresponding sash edges together to move in unison, and swinging arms upon which said sashes are mounted.
3. The combination with a window frame of a pair of sashes therein, sliding connections between corresponding edges of said sashes and the window frame, means for connecting said corresponding sash edges together to move in unison, and swinging arms upon which said sashes are mounted, said arms being pivotally mounted at a common point near one end of the window frame and the arms for one sash being longer than the arms for the other sash.
4. The combination with a window frame, of a pair of sashes therein, said sashes being mounted for sliding movement relatively to said window frame and corresponding edges of said sashes having pivotal connections with the opposite sides of said window frame whereby said sashes may be slid bodily relatively to said window frame and also swung about corresponding edges extending between the sides of said frame, means for connecting said corresponding edges of the sashes together so as to slide in unison and

means for supporting said sashes so as to permit the same to swing about said pivotally connected edges and also to permit said edges to slide between the sides of the window frame.

5. The combination with a window frame of a pair of sashes therein, sliding connections between said sashes and the window frame, means for connecting corresponding sash edges together to move in unison, and swinging arms upon which said sashes are mounted, said arms being pivotally mounted upon the window frame and the arms for one sash being longer than the arms for the other sash, and said arms being pivotally connected at their outer ends to said window sashes.

6. The combination with a window frame of longitudinally extending guideways at the sides of said frame, a pair of window sashes in said frame, pins at the upper corners of said sashes, said pins sliding in said guideways, rods also sliding in said guideways and mounted upon said pins, and arms pivotally connected to said frame near the upper edge of the upper sash when said sash is in a closed position, said arms having their lower ends pivotally connected near the middle of the sides of said sashes.

7. The combination with a window frame, of a pair of sashes therein, the upper ends of said sashes having sliding and pivotal connections with the window frame, rods connecting said upper ends of said sashes together, said rods also having sliding connection with the window frame, arms 12 pivotally supported at the upper end of the window frame and connected with the upper sash near the middle thereof, and arms 16 also pivoted to the upper end of the window frame and being longer than the arms 12, and extending down to the lower sash and pivotally connected with the same near the middle thereof.

In witness whereof, we hereunto subscribe our names this 19th day of March, A. D. 1915.

BENJAMIN R. COLEMAN.
LEROY B. TAYLOR.
